UNITED STATES PATENT OFFICE.

GEORGE ALBERT LYON, OF PHILADELPHIA, PENNSYLVANIA.

BUFFER.

Application filed October 25, 1921, Serial No. 510,832. Renewed October 20, 1923.

To all whom it may concern:

Be it known that I, GEORGE ALBERT LYON, a citizen of the United States, and resident of Philadelphia, county of Philadelphia, State of Pennsylvania, have made a certain new and useful Invention relating to Buffers, of which the following is a specification, taken in connection with accompanying drawings.

10 This invention, which is a continuation in part of that described in my co-pending application, Serial No. 424,685 filed November 17, 1920, relates especially to resilient buffer or bumper devices for automobiles or other vehicles in which the spring steel or other resilient strips or members which may comprise end loops and integral or other attaching members have connected thereto a contact member having vertically separated 20 or extended contact portions which have angularly bent or arched stiffening portions or sections so as to have considerably greater stiffness. This contact member may be forged or stamped out of a suitable sheet or 25 piece of spring steel or the like and may be formed and shaped up in presses or by drop forging methods which may in some cases suitably thicken and strengthen certain parts of the contact member and, if desired, 30 form stiffening ribs or edge flanges on various parts of the same where additional strength or stiffness is desirable. In many cases it is advantageous to have this contact member adjustably or definitely connect the 35 lateral portions of the buffer front to which the ends of the contact connecting member may be clamped, bolted, or otherwise secured and for these purposes it is advantageous to form the connector portions of 40 these co-operating strips or members of the buffer with more or less intermeshing or co-operating aligning cross section as by angularly bending or arching the same so that their alignment is promoted as well as considerably increasing their stiffness and strength 45 against collision impact. Such contact connecting members may in some cases have two or more vertically separated contact portions and may have adjacent the central part of the buffer a generally diamond shaped or lenticular outline around which the generally parallel or uniform width contact portions may extend. If desired, however, several substantially parallel contact 50 portions or plate sections may extend across the central part of the buffer and be formed

of angularly bent or arched stiffened cross section with or without edge ribs or flanges to further stiffen the same. The lateral connecting portions of these contact connecting members may in many cases be clamped to the co-operating connector portions of the other buffer strips or members and, if desired, integral clamping members or portions may be formed on the ends of this connecting member to more or less extend around or enclose the co-operating buffer strips and adjustably or otherwise connect them thereto.

In the accompanying drawings showing in 70 a somewhat diagrammatic way various illustrative embodiments of the invention

Fig. 1 is a front perspective view of one form of buffer.

Figs. 2 and 3 are enlarged transverse 75 sections thereof taken along the lines 2—2 and 3—3.

Fig. 4 is a front perspective view of another illustrative construction.

Fig. 5 is an enlarged transverse section 80 thereof taken along the line 5—5 and

Fig. 6 is a front perspective view of still another construction.

The automobile buffer may have any desired or suitable construction and preferably 85 comprises one or more pieces of spring steel strip which may in some cases be advantageously arranged in overlapping or reinforcing position as in the standard Lyon type buffer. As indicated in Fig. 1 the 90 spring strip buffer members may comprise end loops 3, 7 and, if desired, the co-operating attaching members 1, 5 may be integral therewith and joined to the end loops by the curved resilient portions 2 and 6, of the 95 strips. These strips may advantageously comprise inturned connector portions extending toward or across the central part 100 of the buffer front and, as indicated, these connector portions may be given a stiffened reinforced cross section as by arching or angularly bending them from a point adjacent the end loops which are in most cases left flat so as to secure a maximum resilient bending action. If desired, these connector portions may extend inward to or adjacent 105 the co-operating attaching members of the buffer and may end at about the points 4, 8 so as to be adjustably or permanently clamped or connected to the co-operating 110 contact connecting member which may advantageously have a vertically wide con-

tact face at least adjacent the centre of the buffer. A diamond shaped contact member is shown in Fig. 1 as comprising several separated contact faces or portions such as 11, 5 each of which may comprise several angularly bent stiffened faces 13 as shown in Figs. 1 and 3. This materially increases the stiffness of the member and also improves its appearance especially where a substantially diamond shaped hole or central aperture 12 is formed in this contact connecting member. These angularly bent faces 13 may merge together adjacent the ends of the connecting member 17, 18 which, as indicated 10 in Fig. 2, are given a similar angularly bent cross section in which the two sides or portions may be arranged at an angle of 120 to 130° more or less. These different angularly bent members thus resemble to a considerable extent the diamond bar type of buffer and where these angularly bent or other aligning cross section members overlap or co-operate they have an important aligning action when clamped or bolted together 15 so as to materially promote the vertical alignment of the co-operating members. One or more enclosing clamping devices such as 14, 15 may be arranged around the connector portions on each side of the buffer so as to tightly clamp them together when the co-operating bolts 16 are tightened. This arrangement allows the end loops to be laterally adjusted and securely clamped in adjusted position so that the buffer can be used with automobile frames 20 having the usual range of widths.

Fig. 4 shows another illustrative arrangement in which the inturned connector portions 23 extending inward from the end loops are shown as having arched stiffened cross section corresponding to the arched connector portions 20 adjacent the ends 21, 22 of the contact connecting member 18. This member may, as indicated, have several 40 substantially parallel contact portions or faces 19 each of which may be formed with arched or circularly bent cross section as indicated in Fig. 5, this cross section being carried out in the curved or angularly bent junction portions 20 which are thus considerably stiffened and strengthened against collision stresses. Generally similar clamping or connecting devices 25 may be used in this case to adjustably or otherwise clamp 45 the co-operating or connecting portions of the buffer together and hold them substantially rigidly in adjusted position.

Fig. 6 shows still another illustrative arrangement in which the contact connecting member is of generally lenticular shape and has a similarly shaped central opening 26, if desired. The upper and lower contact portions of this member may each be of angularly bent or diamond bar cross section, 50 the angularly bent faces 13 being arranged

about as indicated in Fig. 2. The outwardly extending connector portions 27, 28 may be of similar angularly bent stiffened cross section so as to have desirable aligning co-operation with the connector portions 9, 10 70 connected to the end loops 3, 7 of the buffer strips. These connector portions may be clamped or bolted together in any suitable way and one or more clamping devices such as 14 may be used in connection therewith 75 so as to hold the strips tightly in adjusted position when the bolts 16 are tightened.

This invention has been described in connection with a number of embodiments, forms, proportions, parts, arrangements, 80 materials, methods of manufacture, connection and use, to the details of which disclosure the invention is not of course to be limited, since what is claimed as new and what is desired to be secured by Letters Pat- 85 ent is set forth in the appended claims:

1. The automobile buffer comprising two spring steel strip members each having a rearwardly extending attaching member, and end loop and an inwardly extending 90 connector portion having a forwardly bent V-sectioned stiffening aligning cross section, a co-operating contact connecting member of spring steel plate having outwardly extending connector portions formed with similarly bent V-sectioned aligning cross section co-operating with the connector portions of said spring strip members, said contact connecting member having vertically separated upper and lower contact 100 portions of similarly stiffened angularly bent cross section to form a generally diamond shaped contact member at least three times as high as said strip members adjacent the central part of the buffer, and 105 clamping devices to rigidly hold together the co-operating connector portions.

2. The automobile buffer comprising two spring steel strip members each having an end loop and an inwardly extending connector portion having a forwardly bent V-sectioned stiffening aligning cross section, a co-operating contact connecting member having outwardly extending connector portions formed with similarly bent V-sectioned 110 aligning cross section co-operating with the connector portions of said spring strip members, said contact connecting member having upper and lower contact portions of similarly stiffened angularly bent cross section to form a generally diamond shaped contact member adjacent the central part of the buffer, and clamping devices to rigidly hold together the co-operating connector 115 portions.

3. The automobile buffer comprising spring steel strip members comprising rearwardly extending attaching members, flat sectioned resilient end loops and inwardly extending connector portions having an an- 120 125

gularly bent stiffening aligning cross section, a co-operating open centre contact connecting member of spring steel plate having outwardly extending connector portions formed with angularly bent aligning cross section co-operating with the connector portions of said spring strip members, said contact connecting member having vertically separated upper and lower contact portions of similarly stiffened angularly bent across section to form a vertically extending generally diamond shaped contact member adjacent the central part of the buffer, and clamping devices to rigidly hold together the co-operating connector portions in adjusted position.

4. The automobile buffer comprising spring steel strip members comprising flat sectioned resilient end loops and inwardly sectioned resilient end loops and inwardly extending connector portions having an angularly bent stiffening aligning cross section, a co-operating contact connecting member of spring steel plate having outwardly extending connector portions formed with angularly bent aligning cross section co-operating with the connector portions of said spring strip members, said contact connecting member having vertically separated upper and lower contact portions to form a generally diamond shaped contact member adjacent the central part of the buffer, and clamping devices to rigidly hold together the co-operating connector portions.

5. The automobile buffer comprising spring steel strip members comprising end loops and an inwardly extending connector portion having forwardly bent stiffening aligning cross section, a co-operating contact connecting member of spring steel plate having outwardly extending connector portions formed with similarly bent aligning cross section co-operating with the connector portions of said spring strip members, said contact connecting member having upper and lower contact portions to form a vertically extending contact member adjacent the central part of the buffer, and enclosing clamping devices to hold together the co-operating connector portions.

6. The automobile buffer comprising spring steel strip members comprising end loops and inwardly extending connector portions having forwardly bent stiffening aligning cross section, a co-operating contact connecting member having outwardly extending connector portions formed with similarly bent aligning cross section co-operating with the connector portions of said spring strip members, and clamping devices to hold together the co-operating connector portions.

7. The automobile buffer comprising a buffer front having resilient end loops and inwardly extending connector portions having forwardly bent V-sectioned aligning

cross section and a one piece diamond shaped contact connecting member having vertically separated contact portions adjacent the central part of the buffer and having laterally extending connector portions of similarly bent aligning cross section co-operating with said inwardly extending connector portions.

8. The automobile buffer comprising a buffer front having resilient end loops and inwardly extending connector portions having forwardly bent aligning cross section and a one piece contact connecting member having vertically separated contact portions adjacent the central part of the buffer and having laterally extending connector portions of similarly bent aligning cross section co-operating with said inwardly extending connector portions.

9. The automobile buffer comprising a buffer front having resilient end loops and inwardly extending connector portions and a connected one piece contact member having vertically separated diamond shaped contact portions adjacent the central part of the buffer of forwardly bent stiffening cross section.

10. The automobile buffer comprising a buffer front having inwardly extending connector portions and a connected contact member having vertically separated contact portions adjacent the central part of the buffer of forwardly bent stiffening cross section.

11. The spring steel contact connecting member adapted for use with resilient front strip buffers and formed with vertically separated central portions and with laterally extending connector portions adapted to co-operate with connector portions of the buffer and be clamped in adjusted position with respect thereto, said portions of said contact connecting member being formed with forwardly bent V-sectioned stiffened cross section and forming a substantially diamond shaped central contact portion for the buffer.

12. The spring steel contact connecting member adapted for use with resilient front strip buffers and formed with vertically separated central portions and with laterally extending connector portions adapted to co-operate with connector portions of the buffer and be clamped thereto, said portions of said contact connecting member being formed with forwardly bent V-sectioned stiffened cross section.

13. The contact connecting member adapted for use with resilient front strip buffers and formed with vertically separated central portions and with laterally extending connector portions adapted to co-operate with connector portions of the buffer and be clamped in adjusted position with respect thereto, said central portions of said contact connecting member being formed with angularly bent forwardly convex stiffened cross section.

14. The contact connecting member adapted for use with resilient front strip buffers and formed with vertically separated central portions and with connector portions adapted to co-operate with connector portions of the buffer, said central portions of said contact connecting member being formed with forwardly convex stiffened cross section.
15. The open centre unitary spring steel contact connecting member adapted for use with resilient strip buffers and formed with vertically separated central portions and with laterally extending connector portions adapted to co-operate with connector por-
16. The open centre spring steel contact connecting member adapted for use with resilient strip buffers and formed with vertically separated central portions, said portions of said contact connecting member being of substantially uniform width and formed with forwardly bent stiffened cross section. 20 25
